UNITED STATES PATENT OFFICE.

LEWIS R. LONG, OF PEORIA, ILLINOIS.

SIGN.

Application filed September 5, 1925. Serial No. 54,691.

My invention relates to an advertising sign and more particularly to an automatic changeable sign wherein different signs or indicia are successively presented to view at 5 intermittent periods; the principal object of the invention being to provide a sign of that character which is simple and positive in operation and which will automatically operate for long periods without undue attention to the mechanical parts.

Another object is to provide a sign that may be built up of a number of individual units complete in themselves to provide a sign of any desired length by simply adding 15 more units and coupling the units to a common driving mechanism.

In accomplishing these and other objects of the invention I have provided improved details of structure, the preferred forms of 20 which are illustrated in the accompanying drawings, wherein

Fig. 1 is a front elevational view of a sign, embodying my invention, a part of the lower frame of the sign being broken away to 25 illustrate the driving mechanism.

Fig. 2 is a horizontal sectional view through the sign.

Fig. 3 is an enlarged, detail, elevational view of the lower end of one of the drums 30 and the rotating mechanism therefor.

Fig. 4 is an elevational view of one of the drums, illustrating its mounting, the rotating gears being shown in section.

Fig. 5 is a perspective view of an adjustable coupling for aligning the drums with 35 their driving mechanism.

Fig. 6 is a sectional view through one of the couplings for connecting the drive shaft sections of adjoining units together.

40 Fig. 7 is a sectional view through the transmission gear housing, on the line 7—7, Fig. 8.

Fig. 8 is a vertical, sectional view through the transmission, taken on the line 8—8 of 45 Fig. 7.

Fig. 9 is a horizontal, sectional view through the transmission on the line 9—9, Fig. 8, showing the trip lever in tripped position.

50 Fig. 10 is a diagrammatical view of the electrical mechanism and wiring for the sign.

Fig. 11 is a side elevational view of an

automatic switch for breaking the circuit to the driving motor.

55 Fig. 12 is a perspective view of the trip lever and the driving lug.

Referring more in detail to the drawings:

1 designates a housing or frame preferably constructed of sheet metal, having a 60 bottom 2, a top 3, ends 4 and 5, and an open front 6, surrounded by a frame 7 in which a plurality of indicia-carrying units are supported.

65 Each unit comprises a vertical drum 8 triangular in cross section, the top end of which is rotatably mounted on a stud 9 fixed in a bracket 9' secured by bolts 9'' to a rail 10 which extends substantially the length of the housing to anchor the top of all the drums. The bottom of each of the drums has a supporting shaft 11 (Figs. 3 and 4) journaled in an anti-friction bearing 11' carried in a bearing support 12 fixed to a plate 13 by bolts 13'. Pinned to the shaft 11 is a worm gear wheel 14 having a web or hub portion 15 provided with upwardly projecting bosses 16 which engage the base of the drum. The drum is rotated from the worm gear by a driving stud 17 also projecting from the hub portion 15 at a distance from the shaft 10 and engaging in an opening 18 in the bottom of the drum so that when the worm gear is rotated, the drum is rotated with it.

70 The worm gear is driven by a worm 19 keyed to a drive shaft section 20, which is rotatably mounted in bearings 21 and 22 also carried by the plate 13 at each end of the worm.

75 Supported by brackets 23 on the plate 13 is an oil pan or reservoir 24 for containing a quantity of oil 25 in which the worm rotates to lubricate the moving parts of the drum and prevent undue friction and wear.

80 The parts heretofore described comprise a single unit of the sign, the complete sign comprising as many of these units as may be desired, each having its own individual rotating mechanism and bearing supports.

85 The drive shaft sections 20 of adjoining units are connected at their adjoining ends by couplings 26 (Figs. 2 and 6) which receive adjacent ends of the shaft sections and are secured thereto by tapered pins 27 105 and 27' which extend through apertures 28

in the coupling and apertures 29 in the ends of the shaft sections to form a continuous shaft 30 for driving the drums in unison.

- The drive shaft 30 is driven from a motor 31 through a transmission gearing 32 which may be located at the end of the sign and adjacent the drive shaft 30 and is adapted for rotating the drums intermittently to successively present complementary sides of the drums in alignment at the front of the sign to form a complete sign or advertisement. The drums being triangular in cross section, three signs or advertisements will be successively presented to view at determined intervals controlled by the transmission. The transmission is so timed that complementary sign faces of the drums are aligned at rest for approximately six seconds, between operating intervals of approximately twelve seconds during which the drums are turning. Thus each of the three signs is exposed at rest once a minute.
- The transmission comprises a train of reduction gearing to drive the drums at the required speed, a trip mechanism whereby the reduction gearing is automatically disengaged from the drum rotating mechanism when the complementary sides of the drums are in alignment, and a train of timing gears driven from the reduction gears for setting the trip mechanism. The transmission gearing is contained in a housing 33 (Figs. 7, 8 and 9) provided with a hinged cover 34 through which access may be had to the transmission parts. The transmission gearing is supported within the housing between side frame members 35 and 36 secured in the gear housing 33 by cap screws 37 which extend through openings in the sides of the housing 33 and are threaded into lugs 37' on the frame members 35 and 36.

- The train of reduction gears comprises a worm 38 keyed to the motor shaft 39 and rotatably mounted in bearings 40 and 41 extending from the side frame 36, a worm gear 42 in mesh with the worm and pinned on a shaft 43 carried by the side members 35 and 36, and a pinion gear 44 also pinned to the shaft 43 which meshes with a gear 45 fixed on a sleeve 46 loosely mounted on a driven shaft 47 which is mounted in bearings 48 and 49 in the side frame members. The shaft 47 projects through the frame member 35 and carries a gear 50 pinned thereto which meshes with a gear 51 pinned to a shaft 52 rotatably mounted in the side frame members. Driving connection is maintained between the shaft 52 and the sleeve 46 by a driving clutch member comprising a lug 53 slidably carried in a bearing 54 on the drive sleeve 46. The lug revolving about the shaft 47 engages a complementary clutch member comprising an arm or projection 55 carried by a collar 55'

pinned to the shaft 47 so that as long as the driving lug projects into alignment with the lug, the shaft 47 will rotate at the speed of the sleeve 46.

The shaft 52 is connected with the drum drive shafts by an adjustable coupling 56 (Fig. 5) comprising a disk 57 on the end of the shaft 30 and a disk 58 on the shaft 52, the disks being provided with apertures 59 and 60 respectively. The apertures 59 in the disk 57 are irregularly spaced with relation to those in the disk 58 so that when the complementary sign faces on the drums are in alignment and the transmission mechanism is in correct relation to the drums, bolts 61 and 62 may be inserted into an alignment pair of apertures in the disks and the disks bolted together.

Universal joints 63 and 64 may be inserted in the shafting at each side of the coupling 56.

From the foregoing it will be seen that the motor will constantly rotate the drums, and means must be provided to withdraw the drive lug 53 out of contact with the arm 55 to disconnect the driving connection between the shaft 47 and the sleeve 46 when the sign faces are in alignment, and it is for this purpose I provide the trip lever and the train of timing gears.

The timing gears comprise a gear 65 keyed to the sleeve 46 and meshing with a gear 66 on a shaft 67, mounted between the side frames and carrying a gear 68 which meshes with a gear 69 on a cam shaft 70 rotatably mounted between the side frames in bearings 71 and 72.

The cam shaft is provided with a disk 73 having pins 74 and 75 extending radially from the periphery thereof. The pins 74 and 75 are adapted to engage a trip lever 76 pivotally carried on the sleeve 46. The trip lever comprises a yoke 61 (Fig. 12) pivotally mounted on the sleeve 46 by stud bolts 77 and 78 which extend through bearings 77' and 78' in the trip lever and engage threaded openings 79 in the sleeve 46. The upper end of the trip lever is provided with an arcuate cam 80, over which the pins 74 and 75 may ride to rock the trip lever out of functional position. The lower end of the trip lever carries an ear 80' to which is pinned the slotted head 81 of the drive lug 53. The trip lever is held in functional position by an expansion spring 82, one end of which engages over a projection 83 on the trip lever and the other end of which engages in a socket 84 in an arm 85 on the sleeve 46 diametrically opposite the drive lug 53 so that the arcuate cam is normally held in the path of the pins 74 and 75 and the drive lug in projected position.

Revolution of the pins 74 and 75 is so timed by the timing gears with relation to the revolution of the trip lever on the sleeve

46 that the pins engage the arcuate cam on its fifth and sixth revolutions to cause the trip lever to rock on its pivots against the tension of the spring and withdraw the 5 drive lug out of contact with the arm on the shaft 47 to stop rotation of the shaft and the drums, for it is at this point that the complementary sign faces on the drums are brought into alignment. Thus it will be 10 noted that the drums are at rest for two revolutions of the trip lever and since the pins do not come into contact with the trip lever for four revolutions of the lever, the signs are in motion for four revolutions of 15 the trip lever, the drive lug being held projected by the spring 82 when free from the pins.

Current for the motor is furnished from an ordinary lighting circuit comprising the 20 negative and positive leads 86 and 87 (Fig. 10) connected to a meter 88. One of the leads is connected to a wire 89 leading to the motor and the other to a time clock 90 by a wire 91 and then to the motor through the 25 line 92. Shunted around the time clock by a wire 93 is a switch 94, presently described. The sign is preferably illuminated by lights 95 suspended by brackets 96 in front of the sign. The lights are supplied with 30 current from the wire 97 connected to the lead 86 and by a wire 97' connected to the opposite lead 87. In the wire 97' is a time clock 99 to control the lights as hereinafter described.

35 To provide for economical operation of the sign it is desirable to stop the mechanical operation of the sign at about midnight, and to again start it to operate at, say six o'clock in the morning; and to provide for 40 automatically turning the lights off at daylight and on again at dark. It is for this purpose that I provide the time clocks.

The time clock 99 is in the light circuit and controls the turning on and off of the 45 light at the required time. The other clock is inserted in the motor circuit as required to start and stop mechanical operation of the sign. Should the time clock 90 shut off the current to the motor while the sign is in the 50 act of turning, the drums would not stop with faces lined up to exhibit a sign, and since it is desirable to have one of the signs in position when the drums are at rest, I have provided the circuit 93 shunted around 55 the time clock so that when the time clock has cut off the current of the motor, the motor may yet receive current through the shunt circuit and keep the sign in operation until one set of sign faces is in alignment, 60 after which the shunt circuit is broken through the switch 94 which is operated from the cam shaft 70. The shaft comprises a lever 100 pivotally mounted on the side frame member 36 as at 101, one end of which 65 carries a contact 102 adapted to engage a

contact 103 mounted on the frame member, the other end of the lever riding on a cam 104 fixed on the end of the cam shaft 70. When the drums are in the act of turning, the contacts are held closed as the lever is 70 on the high lobe of the cam, but at the time the sign faces come into alignment, the end of the lever drops into a notch 105 on the cam under tension of a spring 106, one end 75 of which is fixed to the lever and the other to the frame member 36 and the circuit is broken. When the time clock again comes on, the motor again receives current through the time clock.

Attention is also called to the fact that 80 since each drum and its rotating gearing are individual units, any unit may be readily removed and replaced with a new unit in case of breakage or failure of any part of the unit to operate.

85 The drums are also readily detachable from the sign by removing the brackets 5 and lifting the drums off the shaft 8 and drive pin or stud 17, and new drums with new advertising indicia thereon inserted in 90 place of the drums removed, which may then be repainted in the shop and inserted in another sign.

95 The operation of the sign constructed as described is as follows:

The motor 31 drives the worm 38 which drives the worm gear 42, and through it, the 100 pinion 44, which drives the gear 45 and rotates the sleeve 46 to revolve the drive lug 53 which engages the arm 55 to drive the shaft 47. The gear 50 on the shaft 47, meshing with the gear 51 on the shaft 52 connected to the drive shaft 30, rotates the worms 19 and they in turn drive the worm gears to rotate the drums until complementary 105 faces of the drums are in alignment. At this time the first pin on the disk rides on the arcuate head of the trip lever to cause the trip lever to withdraw the drive lug 53 out of contact with the arm on the shaft 47 and stops farther rotation of the drums. The trip lever continues to revolve and moves away from the pin 74 to project the lug 53 again into driving position but as the lug completes its next revolution, it comes into 110 contact with the other pin 75 and the drive lug is again retracted to pass the arm 55 without engaging it. The trip lever on its next revolution will not contact with the pins as they will have been advanced by the timing gears and the drive lug again picks up the arm 55 to continue rotation of the drums to bring the next sign into position. Thus it will be seen that the drums are idle 115 for two revolutions of the trip lever and the travel of the pins 74 and 75 is so timed that the trip lever will make four revolutions before it again strikes one of the pins, this being the time required to bring the next 120 sign into position.

The operation just described is repeated at the proper time intervals during the day and the operation automatically discontinued and resumed at the proper time intervals under control of the clocks, as heretofore described.

What I claim and desire to secure by Letters-Patent is:

1. In a changeable sign, an actuator comprising a web, having a fixed center shaft projected from one of its faces and having a worm gear rim, a drum having thrust bearing on said shaft, and pins on the web member engaging the drum to rotate the drum with the web member, a worm meshing with said worm gear, and means for driving the worm.
2. In a changeable sign a plurality of rotatable drums, an actuator for each drum comprising a web having a worm gear rim, a shaft for supporting the web, a worm for driving the actuator, and means on the web for removably mounting the drum in driving connection with its actuator.
3. In a changeable sign a plurality of rotatable drums each having a shaft socket and a pin socket therein, an actuator for each drum comprising a web having a worm gear rim, a shaft for supporting the web and extending above the face of the web to be received in the shaft socket and a pin protruding from the face of the web and received in the pin socket to secure the drum in driving connection with the web.
4. In a changeable sign a rotatable drum,

an actuator for the drum comprising a web having a worm gear rim, a shaft fixed concentrically of the web, a bracket member in line with the shaft and having a conical seat, a bearing for the shaft receivable in the seat and means for clamping the bearing in the seat.

5. In a changeable sign a rotatable drum, an actuator for the drum comprising a web having a worm gear rim, a shaft fixed concentrically of the web, a bracket member in line with the shaft and having a conical seat, a bearing for the shaft receivable in the seat, a retaining ring encircling the shaft and engaging the bearing, and means for securing the ring to the bracket member.

6. In a changeable sign a rotatable drum, an actuator for the drum, a relatively slow moving shaft in driving connection with the actuator, a shaft in driving connection with the slow moving shaft, an arm on the second named shaft, and a constantly rotating sleeve loosely mounted on the shaft and having a protruding lug slidably mounted thereon adapted to engage the said arm to drive the second named shaft, lug-withdrawing means on the rotating sleeve to withdraw the lug from engagement with the arm, a counter shaft driven from the rotating sleeve and trips on the counter shaft to engage the lug-withdrawing means to effect intermittent operation of the slow moving shaft.

In testimony whereof I affix my signature.

LEWIS R. LONG.
